UNITED STATES PATENT OFFICE.

GREGORY B. WEBB, OF BROOKLYN, NEW YORK, AND ERIC GILZEAN, OF KEARNY,
NEW JERSEY.

COMMUNITY MAUSOLEUM.

Application filed April 14, 1926. Serial No. 101,888.

This invention relates to community mausoleums and more particularly to such mausoleums in which groups of crypts, one above the other, are arranged back to back 5 so as to provide a ventilating passage between the groups.

One of the objects of the invention is to simplify and strengthen the construction of the mausoleum by providing an underlying 10 crossbeam as part of the structure, which supports the rear ends of the crypts. The cross beam may also serve to permit ventilating air to pass between the cross beam and the ends of the crypts and, in the best 15 embodiment of the invention, receives the drainage from the crypts and is supplied with means for disinfecting the drainage.

Another of the objects of the invention is to permit the building of the mausoleum in 20 two or more stories and to provide ventilating passages between the stories and the groups of crypts, so as to permit circulation of air within occupied crypts and between the groups of crypts, without discharging 25 the ventilating air into the hallways at the front of the crypts.

Another object of the invention is to combine with the crypts a series of hollow vertical ventilating posts, which help to support the crypts at one end, which also support the second story of crypts and serve to supply ventilating air to occupied crypts. 30

Another object of the invention is to provide each crypt with a drainage plug with a 35 downwardly sloping floor, the plugs discharging into the ventilating passage between the crypts and into the gutter in the top of the cross beam, the plugs being normally closed but their plugging portions 40 being knocked out and the plugs opened after the crypt is occupied.

With the above and other objects in view, the invention consists in the parts, improvements and combinations more fully pointed 45 out hereinafter.

Turning now to the drawings, which illustrate one embodiment of the invention:

Figure 1, is a vertical cross section thru the mausoleum, extending lengthwise of the 50 crypts and showing two floors of crypts.

Figure 2, is a vertical cross section of the mausoleum, on line 2-2 of Figure 1, extending crosswise of the crypts.

Figure 3, is a horizontal cross-section on 55 line 3-3 of Figure 1.

Figure 4, is a detailed horizontal cross-section, showing the hollow ventilating post, on line 4-4 of Figure 1.

Figure 5, is a vertical cross-section on line 5-5 of Figure 4. 60

Figure 6, is a vertical cross-section, on line 6-6 of Figure 3, showing the air discharge plug for a crypt.

Figure 7, is a cross-section on line 7-7 of Figure 6. 65

Figure 8, is a horizontal section of the drain plug for a crypt, on line 8-8 of Figure 3.

Figure 9, is a vertical section taken on line 9-9 of Figure 8, and 70

Figure 10, is a vertical cross-section of the disinfectant supplying means, taken on line 10-10 of Figure 3.

Referring to the drawings, the community mausoleum is provided with a series of 75 aisles 1, 2, 3, 4, 5, at the ends of which lighting windows 6, may be placed. The aisles are provided with flooring 7, and with marble walls which will be described more fully hereinafter.

The crypts are arranged in groups, back to back, and are separated so as to provide ventilating passages between them. The groups of crypts 8, on the lower floor of the mausoleum, are arranged one above the other with the ventilating passage 9, between the groups. The upper groups of crypts 10, of the upper floor of the mausoleum, are likewise arranged back to back, one above the other, with the ventilating 90 passage 11, between them. The upper ventilating passage receives ventilating air discharged from the lower passage 9. The crypt walls may consist of re-enforced concrete which is poured to form the crypts, 95 or they may be built of slate or other suitable material. The side walls 12, of the crypts serve as solid division walls between them and the ceiling 13 of one crypt constitutes the floor of the crypt above it. The 100 back walls 14, of adjacent groups of crypts form the ventilating passages between the groups, the side walls 12a of the end groups being separated from the wall 15, of the mausoleum so as to provide ventilating passage 16.

Means are provided for supporting each floor group of crypts in a simple and strong manner, avoiding the use of floor beams and floor slabs running lengthwise of the bot- 110

toms of the crypts. As illustrated, in the lower floor a group of three beams is provided, beams 17 and 18, running transversely of and supporting the outer ends of the 5 crypts and beam 19, extending transversely underneath the back ends of the crypts. These beams are preferably formed of concrete. Concrete floor slabs 20 and 21, supported by means of beams 17, 18, are used 10 to support the marble flooring 7, of the aisles of the mausoleum. The central supporting beam 19, supports the backs of adjacent groups of crypts and is separated from the bottoms of the groups so as to provide a ventilating passage over the top of the beam communicating with the ventilating 15 passage 9. A series of piers 22, rests on the beam 19 and transmits the load from the backs of the crypts to the supporting beam, 20 the piers being spaced apart so as to form transverse ventilating passages between the piers.

An upper supporting beam 23, with separating piers 24, supports the backs of the 25 upper groups of crypts. The spaces 24^a, between the upper piers are preferably made less than the spaces 22^a between the lower piers, this helping to divert some of the 30 ventilating air toward the fronts of the crypts forming the upper groups, as will appear more fully hereinafter.

Ventilating air is supplied from the outside atmosphere thru openings 25, at the bottom of the outside wall of the mausoleum, 35 which openings are provided with screens 25^a and chemical pans 25^b. The air then passes over beam 19, thru ventilating passage 9, and part of the air passes around beam 23, into ventilating passage 11, and out thru 40 ventilators 26, 27, in the roof 28, of the mausoleum. The ventilators are provided with screens 26^a, 27^a, and with chemical tanks 26^b, 27^b, through and around which the air passes and is further disinfected on 45 its way out.

The circulation of air may be produced by the warm air rising inside of the mausoleum or fans may be used to convey the air.

The concrete side walls of the lowermost 50 crypts of each group, are reenforced by wiring and rods 29, forming a series of cross-beams, so that when spanning and when supported on lower beams 17, 18 and 19, or upper beams 23^a, 23, 23^b, respectively, the 55 lower crypts and the beams will firmly support the crypts above them. The central beams 19, 23, do away with the need of supporting flooring beams and flooring for the crypts and abundant space is left by beam 60 23, at the top of the groups of crypts of the first floor, to permit room for the workman when casting the top row of the lower groups of crypts.

The beams 19 and 23, are shaped with beveled 65 sides which act as deflectors for the air

currents and provide a structurally economical form of beam.

Means are provided for disinfecting the air currents and drip from the crypts. At the bottom of each crypt, a drip spout 29^a, 70 is arranged, which may be made of terra cotta, the central plug 30, of which is knocked out when the crypt is put into use. The bottom of the crypt is pitched to drain to the drip spout. 75

The central supporting concrete beams 19, 23, have a gutter 31, 32, formed in their respective tops, into which the drip from drip spouts 25^a, drains. These gutters may be filled with disinfecting fluid by means of 80 cups 33, with removable caps 33^a and metal pipe 34, into which formaldehyde may be poured (see Figures 2 and 10). The air circulating over the gutters and disinfectant carries off the fumes thru ventilators 26, 27. 85

Having thus described the means for supplying ventilating air about the outside of the crypts, the means for ventilating the insides of the crypts will be explained. Air for the inside of the crypts is supplied from the ventilating stream at the fronts of the crypts by a system of posts 35, each with a longitudinal hollow passage 36. Each post is preferably cast of concrete integral with the corresponding division wall 12 of the 95 crypts. The post is preferably reenforced by rods 38 and wire 37, and, when completed, extends from the bottom pier 35^a, to the top of the uppermost crypt of the group. It thus helps to support the crypts and particularly the front end sealing slabs 39, and also helps to support the second story of crypts and the upper aisle floor construction. The posts and the front ends of the crypts are rabbeted at each front edge to receive 100 the front ends 39, and mortar is applied at 40, so as to effectively seal the crypts after they are occupied. The post with its broad front face supports the structure, allows room for the ventilating ducts and gives a 105 broad face to which the marble stile may be attached. The division walls between the crypts may be made thin and the posts united to the walls by beveling the sides of the 110 posts.

The hollow passage 36, of each post communicates with the interior of each respective crypt by means of opening or passage 41 (see Figure 5), normally closed by a metal cap 42, which cap can be removed 115 when the crypt is occupied. Air is discharged from the interior of each crypt thru the discharge plug 43, inclining upwardly into the respective passages 9, 11, and normally closed by means of a terra cotta 120 plug 44 (see Figure 6). This plug is also knocked out when the crypt is occupied.

The air for the interior circulation of the crypts is part of the air which comes from the outside thru openings 25, which 130

then passes upwardly thru openings in piers 35^a, into the hollow passage 36, in the vertical posts, then into the crypts thru openings 41, and then outwardly thru the openings in discharge plugs 43, passing thru passages 9 and 11, on its way out thru ventilators 26, 27. Part of the air from the lower passage 9, passes upwardly thru the hollow passages 36, of the posts of the upper groups of crypts in a similar manner. The smaller ventilating spaces 24^a between the piers below the backs of the upper groups of crypts, tend to direct the air to the longitudinal passages thru the vertical posts at the fronts of the upper groups of crypts. The air passes out of the upper crypts thru their discharge plugs, into passage 11, and to the ventilators 26, 27.

Each vertical ventilating post is made with a broad front face 45 (see Figure 4), thus providing a facing on which the marble stiles 46, may be fastened, the stiles being provided with two recesses of different depths, so as to receive the marble crypt front slabs 47, and permit their ready removal. These crypt front slabs are removed and the interior of the crypt exposed when the crypt is to be occupied, and, after occupation, the front end 39, is secured in place and the marble front slab 47, is replaced. It will be observed that the walls of the aisles are thus lined throughout with marble, a space being left between the crypt front ends 39 and the marble lining 47.

Having thus described the invention, it will be understood that changes may be made in the construction and arrangement of the parts, without departing from the principle of the invention.

What we claim is:

1. A community mausoleum comprising in combination with a group of crypts arranged one above the other of another group arranged one above the other and in back of but separated from said first group so as to form a ventilating passage between the groups and a supporting beam arranged below the ventilating passage between the groups and separated from the bottoms of the lowermost crypts of the groups, thereby providing a ventilating opening between the beam and the groups of crypts.

2. A community mausoleum comprising in combination with a group of crypts arranged one above the other of another group arranged one above the other and in back of but separated from said first group so as to form a ventilating passage between the groups and a concrete drain beam arranged below the ventilating passage between the groups and separated from the bottoms of the lowermost crypts of the groups, thereby providing a ventilating opening between the beam and the groups of crypts, the said

beam receiving the drainage from both groups of crypts.

3. A community mausoleum comprising in combination with a group of crypts arranged one above the other of another group arranged one above the other and in back of but separated from said first group so as to form a ventilating passage between the groups, a drain plug at the back of each crypt communicating with said ventilating passage and a concrete drain beam arranged below the ventilating passage between the groups and separated from the bottoms of the lowermost crypts of the groups, thereby providing a ventilating opening between the beam and the groups of crypts, the said beam receiving the drainage from the drain plugs of both groups of crypts.

4. A community mausoleum comprising in combination with a group of crypts arranged one above the other, of another group arranged one above the other and in back of but separated from said first group so as to form a ventilating passage between the groups, and a supporting beam arranged below the ventilating passage between the groups and separated from the bottoms of the lowermost crypts of the groups, thereby providing a ventilating opening between the beam and the groups of crypts, the said groups being arranged in one story of the mausoleum, the second story of the mausoleum containing two similar groups of superimposed crypts with a supporting beam below and between the groups, the beam of the second story lying above and separated from the top of the ventilating passage between the groups of the first story.

5. A community mausoleum comprising in combination with a group of crypts arranged one above the other, of another group arranged one above the other and in back of but separated from said first group so as to form a ventilating passage between the groups and a concrete drain beam arranged below the passage between the groups and separated from the bottoms of the lowermost crypts of the groups, thereby providing a ventilating opening between the beam and the groups of crypts, the said beam receiving the drainage from both groups of crypts, the said groups being arranged in one story of the mausoleum, the second story of the said mausoleum containing two similar groups of superimposed crypts with a concrete drainage beam below and between the groups, the beam of the second story lying above and separated from the top of the ventilating passage between the groups of the first story.

6. A community mausoleum comprising in combination with a group of crypts arranged one above the other and a side wall for each crypt, of a post extending vertically

at the front of the side wall of each crypt, said post having a face portion, a marble wall stile carried by said face portion and a pair of crypt front slabs removably engaging said stile.

7. A community mausoleum comprising in combination with a group of crypts arranged one above the other and a side wall for each crypt, of a hollow ventilating post 10 extending vertically near one end, at the front of the side wall of each crypt, said post being wider than the side wall and provided with a longitudinal air passage and with a plurality of air passages, one for each 15 crypt, communicating with said longitudinal passage and said crypts.

8. A community mausoleum comprising in combination with groups of crypts arranged one above the other, with a division wall 20 between the groups of crypts, of a hollow ventilating post wider than the division wall, extending vertically at the front of the division wall between the groups of crypts, said post provided with a longitudinal air passage, and with a plurality of air passages, one for each crypt, communicating with said longitudinal passage and said crypts.

9. A community mausoleum comprising in combination with a group of crypts arranged one above the other, of a hollow ventilating post extending vertically near one end, at the front of each crypt, said post provided with a longitudinal air passage and with a plurality of air passages, one for each 35 crypt, communicating with said longitudinal

passage and said crypts, said post having a rabbeted portion to receive the front end walls of the groups of crypts.

10. A community mausoleum comprising in combination with two groups of superimposed crypts, with solid division walls between the crypts of a group, the said crypts arranged back to back with a ventilating passage between the backs of the crypts, of a plurality of normally closed air discharge plugs, communicating with said passage, one plug for each crypt. 40 45

11. A community mausoleum comprising in combination with two groups of superimposed crypts arranged back to back with a ventilating passage between, of a plurality of normally closed air discharge plugs, communicating with said passage, one plug for each crypt, the said plugs being provided with upwardly inclined air passages. 50 55

12. A community mausoleum comprising in combination with a group of crypts arranged one above the other and a side wall for each crypt, of a hollow ventilating post 60 extending vertically at the front of the side wall of each crypt, said post being wider than the side wall and provided with a longitudinal air passage and with an air passage for one of said crypts, communicating with said longitudinal passage and said 65 crypt.

In testimony whereof, we have signed our names to this specification.

GREGORY B. WEBB.
ERIC GILZEAN.
